UNITED STATES PATENT OFFICE

146,918

DESIGN FOR A SAFETY RAZOR CASING OR SIMILAR ARTICLE

Clarence P. Hornung, New York, N. Y., assignor
to Consolidated Razor Blade Co. Inc., Jersey
City, N. J., a corporation of New Jersey

Application February 16, 1946, Serial No. 126,611

Term of patent 7 years

(Cl. D22—3)

To all whom it may concern:

Be it known that I, Clarence P. Hornung, a citizen of the United States of America, and a resident of the city, county, and State of New York, have invented a new, original, and ornamental Design for a Safety Razor Casing or Similar Article, of which the following is a specification, reference being had to the accompanying drawing, forming a part thereof, in which

Figure 1 is a top plan view of a safety razor casing or similar article, showing my new design;

Fig. 2 is a side elevational view thereof, and

Fig. 3 is an edge elevational view thereof.

I claim:

The ornamental design for a safety razor casing or similar article, as shown.

CLARENCE P. HORNUNG.
